UNITED STATES PATENT OFFICE

124,975

DESIGN FOR A KNIFE OR OTHER ARTICLE OF FLATWARE

Harry Malinowski, Meriden, Conn., assignor to
The Ellmore Silver Co., Meriden, Conn., a corporation

Application November 15, 1940, Serial No. 96,604

Term of patent 14 years

To all whom it may concern:

Be it known that I, Harry Malinowski, a citizen of the United States, residing at Meriden, in the county of New Haven and State of Connecticut, have invented a new, original, and ornamental Design for a Knife or Other Article of Flatware, of which the following is a specification, reference being had to the accompanying drawing, forming part thereof.

Figure 1 is a front elevational view of a knife showing my new design, the other side presenting the same appearance as the side shown; and

Figures 3 and 4 are sectional views taken substantially on lines 3—3 and 4—4 of Figure 1.

I claim:

The ornamental design for a knife or other article of flatware, as shown and described.

HARRY MALINOWSKI.
